(57) **CLAIM**

The ornamental design for mobile device camera enclosure with keyboard and flip back, as shown and described.

DESCRIPTION

FIG. 1 illustrates a front perspective view of the mobile device camera enclosure with keyboard and flip back, of the present invention;

FIG. 2 illustrates a front elevational view of the mobile device camera enclosure with keyboard and flip back, as shown in FIG. 1;

FIG. 3 illustrates a back elevational view of the mobile device camera enclosure with keyboard and flip back, as shown in FIG. 1;

FIG. 4 illustrates a left side elevational view of the mobile device camera enclosure with keyboard and flip back, as shown in FIG. 1;

FIG. 5 illustrates a right side elevational view of the mobile device camera enclosure with keyboard and flip back, as shown in FIG. 1;

FIG. 6 illustrates a top plan view of the mobile device camera enclosure with keyboard and flip back, as shown in FIG. 1;

FIG. 7 illustrates a bottom plan view of the mobile device camera closure with keyboard and flip back, as shown in FIG. 1.

FIG. 8 illustrates a back perspective view of the mobile device camera enclosure with keyboard and flip back, of the present invention shown in an alternate configuration;

FIG. 9 illustrates a back perspective view of the mobile device camera enclosure with keyboard and flip back, of the present invention shown in an alternate configuration;

FIG. 10 illustrates a back perspective view of the mobile device camera enclosure with keyboard and flip back, of the present invention shown in an alternate configuration; and,

FIG. 11 illustrates a front perspective view of the mobile device camera enclosure with keyboard and flip back, of the present invention shown in an alternate configuration.

The broken lines in the drawings depict environmental subject matter only and form no part of the claimed design.

1 Claim, 7 Drawing Sheets
